INTERNAL MIX SPRAY GUN

William P. Dalrymple, Rochester, N. Y., assignor
to American Brake Shoe Company, New York,
N. Y., a corporation of Delaware

Application December 3, 1947, Serial No. 789,481

2 Claims. (Cl. 299—140.1)

1

This invention relates to spray guns of the type utilized for spraying paint and the like surface coating materials, and particularly the invention relates to the kind of spray guns that have been termed internal mix guns.

In spray guns of the internal mix type it has heretofore been customary to discharge the mixture of air and paint from the internal mixing chamber into a relatively long and narrow slot extended transversely of the discharge orifice of the spray head, and this arrangement results in the production of a relatively long and narrow spray pattern which is desirable in most types of paint supply work. In prior spray guns of the aforesaid character, this long narrow spray pattern has been relatively fixed in size and form so that such spray guns were not adapted for use where a smaller spray pattern was required. It is therefore an important object of the present invention to enable the long and narrow spray pattern of such an internal mix spray gun to be varied as to form, and related objects are to enable the length of such a spray pattern to be materially reduced, and to enable this to be done in a simple and expeditious manner.

Other and further objects of the present invention will be apparent from the following description and claims and are illustrated in the accompanying drawings which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is a vertical sectional view taken through a spray gun embodying the features of the invention.

Fig. 2 is a front elevational view of the spray head as viewed from the right in Fig. 1.

Fig. 3 is a diagrammatic view illustrating the normal spray pattern attained by the spray gun illustrated in Figs. 1 and 2; and

Fig. 4 is a diagrammatic view illustrating a modified form of the spray pattern that may be attained with the spray gun of Figs. 1 and 2.

For purposes of disclosure the invention has been illustrated in Figs. 1 and 2 as embodied in a pistol-grip type of spray gun of the same general construction as the spray gun disclosed in my

copending application Serial No. 734,819, filed March 14, 1947. This spray gun has a main body 10 with a downwardly extending handle 11 at what may be termed the rear end of this body. At the forward end of the body 10, an adaptor fitting 12 is secured in place on the body 10 by means including a cap screw 13, and at the forward end of the fitting 12, a spray head 15 embodying the present invention is secured in place by a threaded retaining collar 16.

The paint supply is conducted into the fitting 12 at the lower end thereof through a paint supply inlet pipe 17 which opens upwardly into horizontal passage 18 formed in an internal nozzle member 20 that is threaded into the forward face of the fitting 12 so as to abut the forward face thereof. The outer surface of the internal nozzle 20 is engaged by the spray head 15, and the spray head 15 is held in place in such engagement by the retaining collar 16. The passage 18 tapers to a reduced discharge end 22 that is disposed within a mixing and discharge orifice 24 formed in the head 15. The orifice 24 extends forwardly and at its outer end opens into a narrow transverse slot 25 formed in the forward end of the head 15. The slot 25 is disposed in a plane passing through the axis of the orifice 24 and the slot 25 is formed so that the bottom wall thereof is arcuate in shape.

The flow of paint through the nozzle 22 is controlled by a needle valve 28 that extends rearwardly and is adapted to be opened by a main control lever 30 in the manner described in my aforesaid copending application, and when the valve 28 is opened, the paint is withdrawn or aspirated through the nozzle 22 by the passage of pressure air about the nozzle 22 and into the discharge orifice 24. Such pressure air is supplied through a passage 32 formed in the handle 11 as described in my aforesaid copending application, and a main valve 34 is arranged to control such air passage and is in turn controlled by the main control lever 30. The air which passes the main valve 34 is discharged upwardly through an adjustable sleeve valve 35 and into a horizontal passage 36 that extends forwardly in the body 10 so as to open into the fitting 12. At the forward end of the fitting, such air normally passes through a passage 37 and into an annular distributing groove 38 formed in the forward face of the fitting 12. From the annular distributing passage or groove 38, such air passes through angular bores 39 formed in the nozzle 20 and into a chamber 40 formed about the outer end portion 55 of the nozzle 20 and within the head 15. It is

the air that is thus supplied which acts to withdraw or aspirate the paint from the nozzle 22, and as the mixture of paint and air leaves the orifice 24 and passes through the transverse slot 25 the mixture is so directed that it normally assumes the relatively long and narrow spray pattern P-1 as shown in Fig. 3, the long axis of the pattern P-1 being parallel to the slot 25.

Under the present invention, this normal spray pattern may be modified in a simple manner when this is desired, and to attain this result, use is made of an adjustable control valve which forms a part of the spray gun illustrated in my aforesaid copending application. Thus the spray gun has a supplemental air passage 45 formed in the fitting 12 so as to communicate with the forward end of the passage 36. This passage 45 is controlled by a needle valve 46 that extends into the passage 36 and is adapted for adjustment by a knurled operating head 47 disposed at the rear end of the body 10. The forward end of the passage 45 opens into an annular distributing groove 48 formed in the forward face of the fitting 12, and under the present invention, the head 15 has an annular chamber 50 in its rear face which communicates with the chamber 48. From the annular chamber 50, the pair of passages 52 are formed in the plane of the slot 25 so that the forward ends of the passages 52 open into the slot 25 on opposite sides of the orifice 24. These passages 52 converge upon the axis of the orifice 24 so that when the valve 46 is opened, the air discharged from the passage 52 tends to reduce the length of the spray pattern P-1 so that the pattern approaches the form indicated at P-2 in Fig. 4 of the drawings. The extent to which the normal spray pattern P-1 is thus modified is dependent upon the adjustment of the supplemental control valve 46. In the normal use of the spray gun that is thus disclosed, the valve 46 is maintained closed so that the elongated spray pattern P-1 is attained, but when a shorter pattern is desired, the valve 46 is opened progressively until the length of the pattern has been reduced in the desired amount. Such valve operation may of course be easily accomplished, and hence by the present invention, an internal mix spray gun may be readily employed even in those instances where a relatively short spray pattern is to be required for some of the work that is to be done.

From the foregoing description it will be apparent that the present invention materially increases the field of usefulness of an internal mix spray gun, and more specifically it will be evident that under the present invention the spray pattern of an internal mix gun may be readily varied so as to meet the requirements that are presented by the work at hand.

Thus, while I have illustrated and described the preferred embodiment of my invention, it is to be understood that this is capable of variation and modification and I therefore do not wish to be limited to the precise details set forth, but desire to avail myself of such changes and alterations as fall within the purview of the following claims.

I claim:

1. In an internal mix spray head adapted for use with a spray gun having a main air supply passage and a valve controlled supplemental air supply passage, said spray head comprising an outer member having an axial discharge orifice of round cross section formed therein and having a transverse slot formed in outer end of said member in a plane passing through the axis of said orifice, an inner member having a paint discharge nozzle formed therein and positioned within said orifice to cooperate therewith in defining an annular air passage about said nozzle for aspirating paint into said orifice from said nozzle, said inner member having passages therein adapted for connection with the main air supply passage of such a spray gun and to direct air to said annular air passage, a supplemental annular passage formed in said outer member and adapted to be connected to said supplemental air supply passage of such a gun, said outer member having control passages connected to said supplemental annular passage and opening into said slot on opposite sides of said orifice and in a converging relation with respect to the axis of said orifice.

2. In an internal mix spray head adapted for use with a spray gun having a main air supply passage and a valve controlled supplemental air supply passage, said spray head having an axial discharge orifice of round cross section formed therein so as to taper gradually toward a smaller diameter at its outer end and having a transverse slot formed in outer end thereof in a plane passing through the axis of said orifice, said slot having an arcuate rear wall centered at a point falling on said axis forwardly of the slot, means affording a paint discharge nozzle disposed within said orifice to cooperate therewith in defining an annular air passage about said nozzle for aspirating paint into said orifice from said nozzle, means providing passages adapted for connection with the main air supply passage of such a spray gun and to direct air to said annular air passage, means providing a supplemental passage adapted to be connected to said supplemental air supply passage of such a gun, and means providing control passages connected to said supplemental passage and opening into said slot on opposite sides of said orifice in a converging relation to the axis of said orifice, said discharge passages opening into said slot through said rear wall substantially normal to the rear wall at the points at which they open through said wall.

55 WILLIAM P. DALRYMPLE.
